TOY

Alfred H. Laidig, Bloomfield, N. J., assignor to
Joseph Reich, Brooklyn, N. Y.

Application October 7, 1944, Serial No. 557,634

9 Claims. (Cl. 46—195)

1

This invention relates to toys, and more particularly to percussive toys utilizing a bursting membrane for explosive-sound production.

An object of the present invention is to provide an improved and more desirable toy of the character indicated.

Another object of the invention is to provide improved means for mounting and feeding the membrane.

Another object of the invention is to improve upon the sealing and grip means by which the explosive or bursting pressure is confined at the membrane.

Still another object of the invention is to incorporate the membrane roll within the handle or gun stock and to confine the pellets burst from the membrane in use.

Still another object of the invention is to utilize a plunger housing which is slideable both for compressing the piston-actuating spring and for effecting the sealing with respect to the membrane.

Again, an object of the invention is to provide improved cocking and tripping mechanism.

Yet again, an object of the invention is to produce spark ejection from a toy gun barrel as the percussive sound is produced.

Many other objects will appear to those skilled in the art to which the invention appertains as the description proceeds, both by direct recitation thereof and by implication from the context.

While the invention as herein illustrated depicts a toy simulating a pistol, and the description, for brevity and clarity, makes particular reference to the structure as embodied in a simulated pistol, it is to be understood that in so doing the invention is not to be understood as confined thereto, but is applicable to many other forms of containing housings.

Referring, then, to the specific showing selected for illustrating the invention;

Figure 1 is a perspective view of a toy simulating a pistol and embodying the present invention;

Figure 2 is a perspective view of the various parts which are housed in the pistol barrel but shown removed therefrom;

Figure 3 is a sectional view of the toy on a plane longitudinal of the barrel and of the pistol stock or handle;

Figures 4, 5, 6 and 7 are sectional views on lines IV—IV, V—V, VI—VI, and VII—VII respectively of Fig. 3;

Figures 8 and 9 are views similar to Fig. 3, but showing the operating parts in different positions of use; and

2

Figure 10 is a perspective view of the magazine and membrane feeding means.

In the specific embodiment of the invention illustrated in said drawings, the reference numeral 15 designates the toy housing in general which is in a form in the present disclosure simulating a pistol having a barrel 16 and depending handle or stock 17 at the rear end portion of the barrel. For convenience of manufacture, said housing is preferably formed from similar sections juxtaposed on a middle plane through the barrel and stock, said sections being provided with suitable ears and rivets for holding the sections together as commonly employed in construction of sheet metal or hollow toys. The membrane bursting mechanism, the greater part of which is shown alone in Figure 2, is contained within the barrel 16, but with an actuating arm depending into the stock, and the magazine, shown alone in Figure 10, is contained within the stock, but with an upper end of the membrane track extending into the barrel.

Description of the membrane bursting mechanism will be given first. It includes a reciprocating member, for brevity termed reciprocator 18, which is slideable in the pistol barrel. As shown, the said reciprocator is a sheet metal stamping having in the rearward part thereof a cylinder or seamless tube 19 within which air pressure is to be created for bursting a membrane 20 constituting the ammunition, which is preferably a roll of paper the outer convolution of which unrolls and feed longitudinally upwardly through the barrel across the path of rearward movement of the said reciprocator in use. By utilizing a barrel which is, for instance, hexagonal in cross-section, the cylindrical part of the reciprocator may have line contact with the barrel and be guided thereby and be readily slideable therein. Said reciprocator is prevented from rotation and kept aligned by having wings 21 bent laterally therefrom and projecting through slots 22 in the side of the barrel. The tube or pressure cylinder 19 projects from the rear end of the reciprocator and provides a shoulder 23 thereat for preventing displacement of the cylinder forwardly of the reciprocator. At the front end of the said tube or pressure cylinder 19 are ears 24 which are bent outward through a side opening 25 of the reciprocator to prevent displacement in a rearward direction in the reciprocator. In effect, therefore, the pressure cylinder is integral with the reciprocator

and moves therewith as the reciprocator is slid either forwardly or rearwardly.

Internally of the pressure cylinder, said shoulder 23 provides an engaging surface for a rubber or other yielding washer or sealing means 26 the rear end of which projects from the cylinder for engagement against the ammunition membrane as occasion requires. Said yielding washer is shown peripherally grooved with a metallic washer in the groove and projecting peripherally therefrom and engaged at its edge by turned-in edge portions 27 of the cylinder.

At the forward end of the body of the reciprocator is provided a bar 28 projecting toward the front or muzzle end of the barrel within the same. This bar is offset at its forward portion to be somewhat closer to the barrel axis than the cylindrical wall of the body, and at said forward portion said bar has a forwardly and upwardly sloping upper edge constituting a cam 29 for piston-releasing purposes as will appear hereinbelow.

Within pressure cylinder or tube 19 is a piston 30 the periphery whereof has sliding but substantially airtight contact with the wall of said cylinder. From the forward face of said piston there projects a piston rod or bar 31 which extends at least as far forward as the bar 28 from the cylinder and preferably is in substantially sliding facial engagement with the cam-forming end portion of said bar 28. At a properly related position, the upper edge of the said piston bar 31 is provided with a notch 32. A latch 33 lies across both bars so that one part thereof may enter said notch 32 of bar 31 and an adjacent part may ride on the top of the other bar 28 and on cam 29. Said cam 29 acts to raise the latch thereby lifting the latch from the notch of the piston rod and thereby releasing the piston to snap rearwardly under impetus of a coil spring 34 shown in the reciprocator cylindrical housing and bearing against a forward wall 35 of said housing and against the piston 30 at opposite ends of said spring. This tripping of the latch occurs when the piston and its rod are at their most forward position and the reciprocator and its rod are at their most rearward position and the spring under maximum compression.

Said latch has a forwardly extending arm within the barrel, said arm being trunnioned upon a pivot pin or shaft 36 transversely across the interior of the barrel and carried by the said walls thereof. The forward end of the piston rod or bar extends beneath and beyond said shaft 36 and is shown as constituting a toothed rack 37 thereat to mesh with teeth of a pinion 38 carried on said shaft. Next pinion 38 and secured with respect thereto is a friction wheel 39 having a peripheral scratch surface. Against said surface is located a flint or other spark-producing means 40 held thereagainst by a wire spring 41 which is shown projecting upwardly through a hole in the top of the barrel, shaped to constitute a forward sight, and mounted with a loop upon one of the rivets holding the housing sections together. The rear end of said wire spring 41 reenters the barrel through another hole and bears upon the top of latch 33 for holding it depressed and seated in its notch until positively removed by the cam. Rotation of the friction wheel is in a direction which ejects the sparks forwardly from the muzzle when the piston snaps rearwardly rapidly upon release of the latch.

The magazine, shown in Figures 3, 4 and 10 more particularly, is an enclosure and guide with-

in the stock. Said magazine is mounted on the rear edge wall of the stock 17 within the stock and has an opening 42 through the said rear edge wall of the stock for introduction of a roll 43 of ammunition, which, as indicated above, is a rolled membrane strip, and may be paper of desired quality. The opening 42 has a pivoted cover plate 44 and appropriate catch to retain the roll within the magazine. The magazine is provided with flat side walls and a curved edge wall within the stock thus forming a complete pocket for the ammunition roll. Next the rear wall of the stock, said magazine provides an extension wall 45 the upper end of which traverses the barrel and is shaped thereat to form a fixed partition 46 in the barrel and constituting the breech thereof. Along the inner or forward face of extension wall 45 are overlying longitudinal guides 47 which receive and guide the edges of the unrolled last convolution of the ammunition roll to carry the same upwardly across partition or breech 46 and out through a top opening 48 in the barrel.

Feeding of the ammunition membrane upwardly along said extension wall and across the breech, is accomplished by a pusher 49 operated from the trigger or finger-grip 50. As shown, said trigger is of channel formation with the lower side wall portions adapted to enter in space provided between the side walls of the stock and side walls of the magazine. The upper end of said trigger is pivoted on a transverse pin 51, and may thus be squeezed by the user to swing into the stock when firing the pistol. Bent laterally from one channel wall of the trigger into the space between the channel walls, is a transverse bracket 52 to which is secured the lower end of aforementioned pusher 49, and preferably said pusher is of flat resilient metal with ammunition-engaging prongs 53, at its upper end so proportioned, arranged and adapted that as the trigger is drawn inward the upper end of the pusher engages against the strip of ammunition and pushes it upward toward the breech an appropriate distance. The extension or ammunition-guiding wall 45 may be longitudinally grooved, as at 54, to permit the prongs to pierce the ammunition near its edges and thus give accommodation to the points of the prongs to keep them clear of the metal of said guide wall.

The trigger is also connected below its pivot by a link 55 to a depending arm 56 on the reciprocator, said link having a pivot connection 57 with the trigger and a pivot connection 58 with the said arm so that pulling back on the trigger moves the reciprocator rearward and until the washer or cushion 26 engages and seals against the membrane and breech. A spring 59 from the trigger pivot to the said arm 56 tends to move the arm and reciprocator as well as the trigger through link connection 55 back to forward position when released.

Through the center of the breech, so as to register with the hole through the washer or cushion on the end of the cylinder, is a hole 60. Air pressure in the cylinder suddenly created by release of latch 33 and spring 34 and consequent forcing of the piston rearward, bursts the ammunition membrane 29 in front of the breech hole 60, giving the desired explosive sound. The pellet from the membrane may pass through the breech hole and be caught in the rear cavity 61 in the barrel behind the breech. A rear plug 62 at the rear end of the barrel appropriately threaded, is removable for discharging the pellets when de-

I claim:

1. A percussive toy comprising a fixed breech having a hole therein, means for feeding a burstable membrane across said breech over said hole, a reciprocator movable toward said breech and adapted to seal against the same around said hole with said membrane interposed, and means movable in said reciprocator for creating air pressure therein for bursting said membrane.

2. A percussive toy comprising a fixed breech having a hole therein, means for feeding a burstable membrane across said breech over said hole, a reciprocator having a cylinder opposed to said breech and movable toward the same and having a cushioned end engageable against said membrane around the hole in said breech, a spring-loaded piston in said cylinder and the spring of which is compressed by movement of said reciprocator toward the breech, and means for releasing the piston after said reciprocator seals against said membrane.

3. A percussive toy comprising a housing, a reciprocator slideable in said housing, a piston slideable in said reciprocator, a fixed breech wall in the housing against which the reciprocator is limited in rearward sliding movement, a latch holding the piston from sliding while said reciprocator slides rearward toward said wall, a spring compressed between the reciprocator and piston as the reciprocator is slid rearward, and means releasing said latch from holding said piston substantially simultaneously with engagement of the reciprocator with the breech wall.

4. A percussive toy comprising a housing, a reciprocator slideable in said housing, said reciprocator having a pressure cylinder as part thereof, a piston slideable in said cylinder, a fixed breech wall in the housing against which the reciprocator is limited in rearward sliding movement, a latch holding the piston from sliding rearward while said reciprocator slides rearward toward said wall, a spring compressed between the reciprocator and piston as the reciprocator is slid rearward, and means releasing said latch from holding said piston substantially simultaneously with engagement of the reciprocator with the breech wall and thereby creating air pressure in said cylinder by spring-actuated rearward movement of said piston in the cylinder.

5. A percussive toy comprising a housing, a reciprocator slideable in said housing, said reciprocator having a pressure cylinder as part thereof, a piston slideable in said cylinder, a fixed breech wall in the housing against which the reciprocator is limited in rearward sliding movement, means for sliding said reciprocator rearwardly, a latch holding the piston from sliding rearward while said reciprocator slides rearward toward said wall, a spring compressed between the reciprocator and piston as the reciprocator is slid rearward, means releasing said latch from holding said piston substantially simultaneously with engagement of the reciprocator with the breech wall and thereby creating air pressure in said cylinder by spring-actuated rearward movement of said piston in the cylinder, and means for returning the reciprocator and piston to forward position.

6. A percussive toy comprising a housing, a re-

ciprocator slideable in said housing, said reciprocator having a pressure cylinder as part thereof, a piston slideable in said cylinder, a fixed breech wall in the housing against which the reciprocator is limited in rearward sliding movement, a latch holding the piston from sliding rearward while said reciprocator slides rearward toward said wall, a trigger connected to said reciprocator for sliding said reciprocator rearwardly, a spring compressed between the reciprocator and piston as the reciprocator is slid rearward, means releasing said latch from holding said piston substantially simultaneously with engagement of the reciprocator with the breech wall and thereby creating air pressure in said cylinder by spring-actuated rearward movement of said piston in the cylinder, and means for returning the reciprocator and piston to forward position.

7. A percussive toy comprising a barrel and stock, a reciprocator in the barrel, a breech in said barrel, a magazine in the stock, means for feeding ammunition from the magazine to the breech, a piston for applying air pressure to and for bursting the ammunition at the breech, and a trigger for feeding the ammunition and for sliding said reciprocator into engagement with the ammunition at the breech and a latch for releasing said piston to apply bursting pressure to the ammunition.

8. A percussive toy comprising a barrel having a muzzle at one end and a stock at the other end, a pressure cylinder in the barrel, a breech in the barrel, means for feeding a burstable membrane to said breech, a releasable and spring-loaded piston in the pressure cylinder for applying bursting pressure to said membrane, a piston rod in said cylinder and barrel extending toward the muzzle from said piston and fixed to the piston and sparking mechanism within said muzzle, said piston rod and sparking mechanism having connection in the muzzle remote from the piston for operating said mechanism from the piston rod and thereby ejecting sparks from the barrel substantially simultaneously with applying bursting pressure to the membrane.

9. A percussive toy having an air pressure cylinder and an opposed wall having an opening therein, said cylinder having means at its end for sealing against said wall and around said opening, a piston in said cylinder, a piston rod having a notch outside said cylinder, a latch engageable in said notch, a cam fixed to and movable with said cylinder and adjacent said piston rod constructed and arranged to lift the latch from said notch substantially as the sealing means engages the said wall, and a spring behind the piston for forcing the same toward said wall upon release of said latch from the notch.
